DOOR SAFETY LATCH

Fred M. Schultz, Detroit, Mich., assignor of one-half to Raiford U. Loveless, Detroit, Mich.

Application September 12, 1945, Serial No. 615,870

2 Claims. (Cl. 292—268)

1

My invention relates to a new and useful improvement in a door safety latch adapted for mounting on a swingable door and so arranged and constructed that when the latch is moved to one position the door may be swung open a slight distance to permit persons on opposite sides of the door to see and converse with each other.

Another object of the invention is the provision of a latch of this class so constructed and arranged that when it is swung to a position where the door is slightly ajar the latch will prevent the door from slamming to closed position.

Another object of the invention is a latch so constructed and arranged that when swung to non-open position it will automatically lock the door against swinging to open position.

Another object of the invention is the provision of a latch of this class which may be mounted on doors associated with jams having different sizes and types of moulding so that the latch is universally adapted for all types of swinging doors.

Other objects will appear hereinafter.

It is recognized that various modifications and changes may be made in the detail of structure illustrated without departing from the invention and it is intended that these shall be embraced within the scope of the claims which form a part hereof.

Forming a part in this specification are drawings in which,

Fig. 1 is an elevational view of the door showing the invention applied,

Fig. 2 is a front elevational view of the invention showing it in closed position,

Fig. 3 is a sectional view taken on line 3—3 of Fig. 2,

Fig. 4 is a sectional view taken on line 4—4 of Fig. 2,

Fig. 5 is a view similar to Fig. 3 showing the invention swung to door-opening position.

In the drawings I have illustrated the invention used with a swingably mounted door 7 associated with which is a door frame having a door post or door jamb 8. Fixedly secured to the door jamb 8 is a plate 9 and having a knuckle 10 formed thereon through which is passed a pin 11 which also projects through the knuckles 12 and 13 formed on the swingable latch plate 27. The knuckles 12 and 13 are larger than the pin 11 and larger than the knuckle 10 whereat there is considerable play between the knuckles 12 and 13 and the pin 11. Formed in the plate 27

2

is a longitudinally directed slot 14 terminating at the outer or free end of the plate 27 with the lateral extensions 15 and 16. Formed at the opposite end of the slot is the enlargement 17.

5 Mounted on the door 7 is a plate 18 having the upwardly turned portion 19 terminating in the reduced portion 20 which is provided with an extension in the form of a neck 21 projecting outwardly from which are the arms 22 and 23 to provide a cross head.

When the door is fully closed the plate 27 may be swung to overlie the plate 18 as shown in Fig. 3 and in this movement the cross head will pass through the enlarged portion 17 of the slot 14

15 as will likewise the portion 20 of the member 18. As shown in Fig. 4 the portion 20 is of substantially the same width as the slot 17. The portion 20 is a planar body so as to provide a flat face opposed to the edge of the portion 17 of the slot 14. When the parts are in the position shown in Fig. 3 an inward swinging of the door 7 will cause the plate 27 to swing inwardly slightly until the opposed face of the portion 20 engages the end edge of the slot 17 and thus

25 25 the door is locked against further inward swinging movement. This inward swinging movement is not sufficient to allow the door to clear the door jamb 8 so that the latch thus serves as a lock for preventing the door from being opened.

30 When desired the plate 27 may be swung on its pivot pin 11 until the narrow slot 14 is in registration with the neck 21 whereupon the door 7 may be swung inwardly as shown in Fig. 5. This inward swinging may continue until the

35 neck 21 engages the end of the slot 14. Thus the door may be swung open sufficient distance to allow persons on opposite sides of the door to see and converse with each other while at the same time preventing further opening of the

40 door so that a person cannot enter through the door. When swung to fully open position the plate 27 will drop by gravity downwardly until the notch 15 will engage the neck 21 and thus a closing of the door can not be effected until the

45 plate 27 is lifted slightly to disengage the neck 21 from the notch 15. Consequently, a person may swing the door to open position so that the door is ajar and can not be swung further to open position while at the same time it can not be blown closed by the wind.

The combined width of the slot 14 and the notches 15 and 16 is less than the width of the cross head embodying the arms 22 and 23. In order to release the door for movement to closed position the neck would be raised out of engage-

ment with the edge of the notch 15 or 16 and thereupon the door may swing to closed position, the neck 21 riding along the slot 14 toward the enlarged portion 17.

By forming the plate 18 and its associated parts as described the device may be used on doors associated with door jambs having various types of moulding. For instance, the plate 9 may be moved either inwardly or outwardly relatively to the face of the door 7 and the portions 20 and 21 would still be in a position for cooperating with the swingable latch body 27. In this way I have provided a safety door latch which has the beneficial features enumerated and which may be economically manufactured and which may be easily and simply installed and which is also very easy to use in its various functions.

What I claim as new is:

1. In a door latch mechanism of the class described adapted for use in connection with a swingable closure a plate mounted on the closure in fixed relation thereto; an outwardly extending portion on said plate; a neck extending outwardly from said portion and of less width than said portion; a cross head on the end of said neck, said cross head being of greater width than said neck; a retaining plate adapted for mounting on a stationary body or door post; a latch plate swingably mounted at one end on said retaining plate and having a longitudinally directed slot formed therein, said slot terminating adjacent the hinged end of said plate in an enlargement sufficiently wide for reception of said outwardly extending portion, the face of said portion opposed to the edge of said enlargement being planar, said slot being of less width than said portion and of sufficient width for permitting the sliding of said neck therethrough.

2. In a door latch mechanism of the class described adapted for use in connection with a swingable closure swingable relatively to a stationary door post, a plate mounted on the closure in fixed relation thereto; an outwardly extend-

ing portion on said plate; a neck extending centrally outwardly from the edge of said portion and of less width than said portion; a cross head on the end of said neck, said cross head being of greater width than said neck; an elongated latch plate swingably mounted at one end on said door post and having a longitudinally directed slot formed therein extending substantially from end to end, said slot terminating adjacent the hinged end of said latch plate in an enlargement sufficiently wide for the reception of said outwardly extending portion, face of said portion opposed to the edge of said enlargement being planar, said slot being of less width than said portion and of sufficient width for permitting the sliding of said neck therethrough and of less width than said cross head, the position of said outwardly extending portion and said latch plate being such that, upon swinging of said latch plate, while the door is closed, into position for extension of said portion through said slot enlargement that upon swinging of said door toward open position said latch plate will swing inwardly until the opposed face of said portion engages the edges of said enlargement for preventing further inward swinging of the door.
